UNITED STATES PATENT OFFICE.

FRANK W. SMITH, OF GARDNER, MASSACHUSETTS.

DESIGN FOR A SPOON, &c.

SPECIFICATION forming part of Design No. 28,221, dated February 1, 1898.

Application filed November 13, 1896. Serial No. 612,030. Term of patent 14 years.

To all whom it may concern:

Be it known that I, FRANK W. SMITH, a citizen of the United States, residing at Gardner, Worcester county, Massachusetts, have invented and produced a new and original Design to be Applied to the Handle of a Spoon, Fork, or the Like, of which the following is a specification, reference being had to the accompanying drawings, in which—

10 Figure 1 is a front view of the handle. Fig. 2 is a rear view of the handle.

My design is in two parts. One part, which is illustrated in Fig. 1, is to be applied to one side of the handle, and the other part, which 15 is illustrated in Fig. 2, is to be applied to the other side of the handle.

The design shown in Fig. 1 is composed, essentially, of a plurality of tapering ribs *b*, arranged side by side, the small ends of the 20 ribs running in the direction of a common center. At about one-half the length of the taper these tapering ribs meet a second set of tapering ribs *b'*, arranged in a manner similar to ribs *b*. The two outer ribs *b*, however, 25 run to the bar *d*. Ribs *b* curve downwardly as they become smaller, and ribs *b'* make an upward-and-downward curve as they become smaller, and at the small end of ribs *b'* they are crossed by a bar *d*. At the large end of 30 each rib *b* is a bead *a*, and at the large end of each rib *b'* is a bead *e*. At the opposite side of bar *d* from that upon which are arranged the ribs *b b'* are a plurality of elongated beads *f*.

The design for the opposite side of the handle is in some respects the reverse of the one 35 just described. This is composed, essentially, of a plurality of tapering depressions arranged side by side and separated by raised lines *g*. The small ends of these depressions run in the direction of a common center. At about one- 40 half the length of the taper these tapering depressions meet a set of tapering ribs *h*, which do not curve as do the corresponding ribs upon the other side. A bar *j* crosses the small end of ribs *h*, and elongated beads *f* are arranged 45 upon the opposite side of bar *j* from that upon which are arranged the ribs *h*. The elongated beads *f* are common to the design upon both sides of the handle. The group of beads *a* and ribs *b* I mark A, and the group of beads 50 *a* and ribs *b'* are marked B. The group of depressions separated by the raised lines *g* are marked D, and the group of ribs *h* are marked E.

I am aware of the patent to Hart, No. 23,861, 55 dated December 11, 1894, and disclaim all shown therein.

What I claim is—

The design for a spoon, fork or the like substantially as shown and described.

FRANK W. SMITH.
